MACHINE FOR MAKING BOX TOPS AND BOTTOMS

Alfred J. Ambrose, Yakima, Wash., assignor to
Cascade Lumber Company, a corporation of
Washington

Application August 14, 1933, Serial No. 685,046

10 Claims. (Cl. 144—7)

This invention relates to machines for making tops and bottoms for wooden boxes such as are used for crating apples, peaches, berries and the like, which are made up of thin boards arranged side by side and joined together across their ends by narrow wooden cleats; the present invention being an improvement upon the machine described and illustrated in my application filed October 24, 1932 under Serial No. 639,184.

10. The machine of the above mentioned application, briefly described, comprises a hopper with partitions dividing it into compartments, each for containing a supply of boards. It also comprises two hoppers each for containing a supply of cleats and there are feed slides manually reciprocated to feed the boards and cleats from their respective hoppers into an assembling frame for permanent connection. Provision is made also for passing the cleats across glue applying rolls as they enter the assembling machine, thereby to apply glue for connecting each pair of cleats with a corresponding set of boards. A press block is operable in synchronism with the feed slides against the parts after they have been assembled in the frame thereby to advance and to retain them under compression until the glue has sufficiently set to permanently join the parts.

It is the principal object of the present invention to provide a machine for the same purpose as that of the machine of the above described pending application, and which is quite similar in its construction and mode of operation but which is different mainly in that it is fully automatic in all of its operations and requires only that the attendant keep the hoppers properly supplied with boards and cleats.

It is also an object of the present invention to provide an improved means in the nature of a crank shaft for reciprocally actuating the press block in synchronism with the feed slides thereby to provide for receiving assembled sets of boards and cleats beneath it on each upward movement to be forced down under compression within a guide chute where they are held while the glue sets and are subsequently delivered from the machine as finished units.

A still further object of the invention is to improve upon the glue applying means so that the feeding of glue is positive and definite in amount delivered to each cleat.

Still further objects reside in the provision of novel driving and timing means for operating the feed slides and press block.

Other objects reside in the improved details of construction and in the combination of parts

and in their mode of operation, as will herein-after be described.

In accomplishing these and other objects of the invention, I have provided the improved details of construction, the preferred forms of which are illustrated in the accompanying drawings, wherein—

Fig. 1 is an elevation of the present machine.

Fig. 2 is a horizontal section through the assembling frame, as on line 2—2 in Fig. 1.

Fig. 3 is a section on the line 3—3 in Fig. 1, illustrating the stop latch mechanism.

Fig. 4 is a plan view of the machine.

Fig. 5 is a plan view of the cleat feed slide removed from the machine.

Fig. 6 is an elevation of one of the glue containers and feed mechanism.

Fig. 7 is a sectional detail of the glue feeding means, as seen on line 7—7 in Fig. 6.

Fig. 8 is a sectional view substantially on line 8—8 in Fig. 4.

Fig. 9 is a vertical section, on line 9—9 in Fig. 4 illustrating the board feed slides and the press block.

Fig. 10 is a perspective view of a finished box section.

Referring more in detail to the drawings—

The frame structure of the present machine, in plan view, is of right angular form as seen best in Fig. 4, with the board and cleat assembling frame located at the vertex. The hoppers and feed slides for advancing the boards and cleats are contained respectively, within the two wing portions of the frame. The boards for forming the box sections are contained in a rectangular hopper 1. This hopper has a supporting structure comprising horizontally mounted, parallel side rails 2—2' supported at their inner ends from their assembling frame structure, presently described, and at their outer ends by a cross bar 3 to which supporting legs 4 are attached.

The frame in which the sets of cleats and boards are assembled and joined is made up of four vertically arranged angle iron guide beams 5, 6, 7 and 8, as seen best in Fig. 2. These beams define the corners of a vertical guide way within which the boards and cleats as assembled are placed under compression to insure their proper connection. The angle beams as seen in Fig. 8, pass downwardly through an opening 9 in the floor 10 on which the machine is mounted and they may extend to any distance within reasonable limits.

The frame for mounting the cleat feed slide and for the support of the glue applying means

and the cleat containing hoppers comprises parallel opposite side beams 14—14' attached rigidly at their inner ends to the assembling frame and joined at their outer ends by cross bar 15 to which supporting legs 16 are attached.

The box sections, which may be either tops or bottoms, made by the present machine comprises three thin boards 17 as shown in Fig. 10, joined across their ends by the cleats. Preparatory to assembly, a supply of such boards are placed in stacks in the hopper 1. The hopper is of rectangular form and is mounted upon the frame beams 2—2' close to the assembling frame and it is longitudinally divided by partitions 18 into compartments of like size and each adapted to contain a stack of boards therein. The partitions preferably are adjustable in the hopper to accommodate boards of different widths. The three compartments formed by the partitions are open at their lower ends and the stacks are supported by the feed slide which operates beneath the hopper.

The feed slide whereby the boards are fed into the assembling frame comprises three horizontally disposed plates 20 attached at their outer ends to a block 21 that is supported for reciprocal action between the frame beams 2—2' by rollers 22 at its opposite sides, movable within guides 23 formed between spaced ribs 24 fixed longitudinally to the inner sides of the beams. At their inner ends, the three plates 20 rest upon a transverse roller 25 which is mounted across the inner end of the frame structure below the hopper end adjacent the assembling frame as seen in Fig. 9. This roller, together with the rollers 22 support the feed slide for reciprocal action.

All of the plates 20 are of like size and are adapted when the slide is at its outer limit of travel, each to underlie and support a stack of boards in the hopper. Each plate is longitudinally recessed in its top surface as shown at 20a in Fig. 9 for reception of the lower board of the stack. The outer end of the recess is open and the inner end terminates in a vertical shoulder 27 adapted to engage against the end of the board resting therein when the slide moves inwardly thereby to cause the board to be pushed from the lower end of its stack into the assembling frame. The arrangement of the feed slide is such that when it is actuated to its outer position, as seen in Fig. 1, the three plates are then properly positioned to receive the lowermost boards of the supply stacks within the recessed end portions. Then, as the slide advances inwardly to the dotted line position of Fig. 1 the lowermost board of each stack is pushed from the hopper and the supporting plate carries it into the assembling frame. The bottom edge of the inner end wall of the hopper is so spaced above the plane of the slide that but one board may be advanced from each compartment with each reciprocal action. When the feed slide returns outwardly, the three boards that have been advanced into the assembling frame on the plates, are retained against return movement, each by a stop bar 35 slidably supported in guides 36 for limited vertical movement. At its upper end each bar has a laterally directed portion 37 overlying the end wall of the hopper for limiting its downward movement and at its lower end has an inwardly curved portion 40 acting as a runner beneath which the board is advanced by the slide. As the slide moves inwardly the runners merely ride upon the advancing boards and finally drop

down back of their ends, then as the slide moves outwardly the stops 35 engage the ends of the boards and hold them against return movement. Thus, the three boards, moved into assembling frame, will be pushed from the feed slide plates 20 and dropped into the frame in proper relationship for their being assembled with the cleats.

The cleats 45, which are applied across the opposite ends of the boards to complete the box bottom or top, are arranged horizontally in two supply stacks as seen in Fig. 4. These stacks extend in the longitudinal direction of the frame beams 14—14' and are spaced apart the same distance that the cleats assume in the finished box section. Each stack of cleats is supported at its ends in hopper guideways 47—47' which are attached by means of plates 48 to the opposite side beams of the supporting frame. These guideways are open at their lower ends and the two stacks of cleats supported thereby rest, respectively, upon horizontal feed bars 49—49', parallel to each other, and extended in the direction of the cleats, and which are fixed upon a feed block 50 reciprocally movable in the frame toward and from the assembling frame. The block 50 has supporting rollers 51 at its opposite sides contained in guideways 52 provided in the inner faces of the frame side members 14—14'. Each of the feed bars 49—49' is recessed along its outer end portion as at 49a, and each recess has an inner end shoulder 56. When the cleat feed slide 50 is at its outer position of movement as seen in Fig. 8, the recessed ends of the feed bars are disposed directly beneath the two stacks of cleats and the lowermost cleat of each stack rests within the recess of the bar beneath it. Then, as the slide moves inwardly to the dotted line position of Fig. 6, the two contained cleats are carried on the bars into the assembling frame. Stop bars 58 substantially like those used in connection with feeding of the boards into the machine, are employed in connection with the hoppers 47. These stop bars are vertically slidable in guides 59 attached to the assembling frame and they have end portions 61 beneath which the cleats are pushed on entering the assembling frame and which ride upon the cleats as they enter, then drop back of the outer ends when the slide reaches its limit of travel, thus preventing the cleat returning with the feed bars.

For the purpose of applying a strip of glue to each cleat as it is delivered into the assembling frame, I employ means as shown in Figs. 4, 6 and 7, wherein a glue container 63 is associated with each hopper and each container has a downwardly directed delivery spout 64, provided with an opening 65 from which glue may be delivered onto the top surface of a cleat advanced on the feed bar. Within the spout is a pump, as seen in Fig. 7, consisting of two intermeshing gear wheels 66 and 67, revolvably fitted in a pump chamber 68. One gear has a driving shaft 69 extended from the housing and equipped at its outer end with a toothed wheel 70 adapted for rolling contact with the advanced cleats. Thus, as each cleat is advanced into the assembling frame, it engages the wheel to thereby rotate the pump gears, which in turn operate to deliver a ribbon of glue from the opening 65 onto the top of the cleat. Therefore when the boards 17 and cleats are delivered alternately into the assembling frame and are stacked in that order, the glue operates to attach the cleats to the corresponding set of boards.

For actuating and for synchronizing the movements of the feed slides for the board and cleats, I have provided a driving mechanism as seen best in Figs. 1 and 4, wherein 71 designates a horizontal shaft revolubly mounted below the floor in bearings 72. On one end of the shaft is a driving sprocket wheel 73, fixed on the shaft between two sprocket wheels 74—75 of like size, which are freely revoluble on the shaft. At its other end, the shaft 71 has a crank arm 78 fixed thereto and this is connected pivotally, at its end, with a link 79, which, in turn, is pivotally attached at its other end to a lever 80, fixed on a shaft 81 revolubly supported above the floor, in bearings 82 and 83. The length of the crank 78 and length of lever 80, are such that rotation of the crank 78, causes an oscillatory movement of the lever 80 with a consequent oscillating action of shaft 81. The shaft 81 extends transversely beneath that part of the frame which mounts the feed slides for the cleats, and at one end it has a beveled gear wheel connection 85, as seen in Fig. 4, with a shaft 86, which is revoluble in bearings 87, and extends transversely beneath that part of the frame that mounts the feed slide 21. The feed slide 50 is connected by a link 90 with the outer end of a lever 91 fixed on shaft 81. Likewise, feed slide 21 is connected by a link 92 with that upper end of a lever 93 fixed on the shaft 86. Therefore, since oscillation of shaft 81 effects a like action of shaft 86 by reason of the geared connection, the action of the feed slides will be synchronized so that as the slide 50 moves two cleats into position in the assembling frame, the slide 21 likewise moves a set of boards into the frame and deposits them on the cleats.

At the start of each operation, a friction block 95 is fitted in the guideway as seen in Fig. 8, and the stack of boards and cleats is built up on this block. The stack is gradually forced downwardly under the action of a reciprocating head or presser 96 contained in the upper end of the guideway, and which also is synchronized in its reciprocating movements with the feed slides. This block is connected by a connecting rod 97 with a crank shaft 98 which is revolubly mounted, as seen in Fig. 9, in bearings 98', and extends transversely through the upper end of the frame. At its outer end the shaft is equipped with three sprocket wheels 99, 100 and 101; the latter being fixed on the shaft between the others which are freely revoluble thereon. The central sprocket 101 is aligned with the driving sprocket 73 on shaft 71 and the sprocket wheels 100 and 101 are aligned with the sprockets 74 and 75; and there are chain belts 103 and 104 extended about these aligned sprockets and also over sprocket wheels 105—105' on the main drive shaft 106 that is extended from any suitable source of power, not herein shown. The shaft 106 rotates continuously and drives the two belts in unison.

Supported between the two chain belts, as seen in Fig. 1, is a short length of sprocket chain 110, adapted for driving contact with the sprocket wheel 73 to rotate the shaft 71 for actuation of the feed slides and also for driving the sprocket wheel 101 to rotate shaft 98 to reciprocate the presser block 96. The length of this strip of sprocket chain 110 is exactly such that in passing over these sprockets 75 and 101 it will cause them to rotate once, and that will effect first one complete operation of the feed slides, then a downward and upward reciprocal action of the block 96, whereby the boards and cleats delivered

by the action of the feed slides will be compressed together and the stack of box parts pressed down for reception of the parts that will be fed into the frame with the next action of the slide.

In order to stop the rotation of the crank shaft 98 at a point at which the presser block 96 will be in a raised position, I provide a latch device as seen in Fig. 3. This comprises a pivotally supported latch bar 112 with a lateral shoulder 113 adapted to seat in a notch 114 in a wheel 115 fixed in the crank shaft, thereby to retain the presser in raised position. An arm 112' extends from the bar to a position within the path of travel of the sprocket chain strip 110 so that the bar will be actuated thereby to unseat it from the notch in the wheel as the strip engages the arm; but, as soon as the arm is released, the bar drops again into the notch to stop the rotation of the crank shaft.

With the device so constructed, the feeding operations are automatic, and all parts, through the driving connections shown, are all kept in proper synchronism. The feed slides deliver the boards and cleats into the assembling frame to form a stack in which the boards and cleats alternate. The stack is kept under compression and thereby causes the cleats to become united with their corresponding set of boards by setting of the glue that is applied to the cleats.

Having thus described my invention, what I claim as new therein is—

1. A machine of the character described comprising an assembling frame, feed devices for delivering sets of boards into the frame, feed devices at different levels for delivering sets of cleats into the frame transversely of the boards, means for applying an adhesive to certain faces of the cleats as they are delivered, and a driving means common to both feed devices whereby they are caused to deposit sets of boards and cleats alternately in stacked relation in the assembling frame.

2. A machine of the character described comprising an assembling frame, feed devices for delivering sets of boards into the frame, feed devices at different levels for delivering sets of cleats with an adhesive applied thereto into the frame transversely of the boards, a driving means common to both feed devices whereby they are actuated to deposit sets of boards and sets of cleats alternately in stacked relation in the assembling frame, and means for advancing the stack in the frame to clear the receiving position after reception of each set of boards and their corresponding cleats.

3. A machine of the character described comprising an assembling frame, feed devices for delivering sets of boards into the frame, feed devices at different levels for delivering sets of cleats into the frame, means for applying an adhesive to certain faces of the cleats as they are moved into the frame, a driving means common to both feed devices whereby they are actuated to deposit the sets of boards and cleats alternately in stacked relation in the frame, and a member operable to apply pressure on the stack to facilitate attachment of the boards to their corresponding cleats by the adhesive.

4. A machine of the character described comprising an assembling frame, feed devices for delivering sets of boards into the frame, feed devices at different levels for delivering sets of cleats into the frame, means for applying an adhesive to certain faces of the cleats as they are

- 5 moved into the frame, a driving means common to both feed devices whereby they are actuated to deposit the sets of boards and cleats alternately in stacked relation in the frame, and a presser head reciprocally operable against the top of the stack to advance it under compression along the frame away from the receiving position. 80
- 10 5. A machine of the character described comprising an assembling frame, hoppers for board stacks, hoppers for cleat stacks, feed devices for delivering sets of boards from the first mentioned hoppers into the assembling frame, feed devices operable for delivering sets of cleats from their hoppers into the assembling frame at a different level and to deposit them transversely of the boards, means for applying an adhesive to the cleats as delivered to effect their attachment to a set of boards, a reciprocally movable presser head, and means for actuating the feed slides and 85 presser head in synchronism to deposit the sets of boards and cleats alternately in stacked relation in the frame and to cause the head to compress and advance the stack from the receiving position after delivery of each set of boards and 90 their corresponding cleats. 95
- 15 6. A machine of the character described comprising an assembling frame forming an elongated guideway, a feed device at a different level whereby board sets are delivered into the assembling frame, a feed device whereby sets of cleats are delivered into the frame into position for joining the boards of each set, means for applying an adhesive to the cleats as they are delivered into the frame, a presser head reciprocally mounted 100 in the guideway and operable across the place of reception of said boards and cleats, a driving means common to the two feed devices and presser head, and whereby the feed devices are actuated to deliver boards and cleats alternately into 105 the guideway in stacked relation, and the presser head is actuated synchronously with the feed devices against the top of the stack to move the stack under compression below the point of reception of said parts. 110
- 20 45 7. In a machine of the character described, an assembling frame forming an elongated guideway, a hopper containing a plurality of board stacks, hoppers containing cleat stacks, a reciprocally movable feed slide for delivering sets of boards into the frame, a reciprocally movable feed slide for delivering sets of cleats into the frame at a different level to deposit them transversely across the ends of the boards, means for applying an adhesive to the cleats as advanced, a crank shaft, a presser head reciprocally actuated thereby, a main drive shaft, a driving shaft with means operatively connected therewith for actuating the feed slides, a sprocket wheel on the main drive shaft, a second sprocket wheel on the crank shaft, a third sprocket wheel on the slide driving shaft, and a belt continuously driven by the sprocket wheel on the main drive shaft, and 115 having a sprocket section thereof adapted to alternately drive the second and third sprocket wheels to cause boards and cleats to be alternately delivered in stacked relation into the guideway and the stack to be advanced under compression by reciprocal actions of the presser head. 120
- 25 8. A machine as in claim 7 wherein the belt operates over idler sprocket wheels on the crank shaft and slide driving shaft and wherein the sprocket section is of such length to cause one functional operation of the feed slides alternately with one reciprocal action of the presser head. 125
- 30 9. A machine as in claim 7 wherein a movable latch device co-acts with the crank shaft to stop its movement after each functional operation of the presser head and wherein the sprocket chain section of the belt engages with and releases said latch to permit driving the crank shaft. 130
- 35 10. In a machine of the character described, the combination with means for delivering sets of boards and means for delivering sets of cleats across the ends of said boards, of a glue applying means comprising glue containers disposed in the path of delivery of the cleats and having base 115 openings beneath which the cleats are advanced, a pump mechanism on each container, a driving wheel for each pump positioned to be driven by frictional contact with cleats as advanced for forced delivery of glue onto the cleats. 135
